UNITED STATES PATENT OFFICE

CHARLES L'ENFANT, OF NEW YORK, N. Y.

CONTAINER

Original application filed February 5, 1926, Serial No. 86,129. Divided and this application filed March 6, 1929. Serial No. 344,726.

This invention relates to containers, its chief object being to provide an improved construction of this character capable of being produced in the form of an original package for cigarettes or other commodities and which will embody certain desired features of simplicity, efficiency and convenience.

The present invention is a division of my renewed application Serial No. 86,129, filed July 2, 1928, which has matured into Patent 1,735,323, granted Nov. 12, 1929.

One object of the invention is to provide a form of container which may be conveniently produced from sheet metal, cardboard or other inexpensive material.

Another object of the invention is to provide a container having a duplex character, capable of holding two separate allotments of commodities, either of the same kind or of different kinds, the container of my present invention comprehending the provision of two separate actuatable article holders arranged in a main case section.

More specifically, my present invention comprehends the provision of a container embodying two separate article holders arranged to constitute complementary end closure portions of the main case section and hinged thereto in such manner as to be capable of being swung outwardly, either one at a time or both at a time, into open position where ready access may be had to the articles which they carry.

A further object of the invention is the provision of an arrangement in which the main casing section is longer at the top than at the bottom and in which separate article holders, adapted to constitute complementary end closure portions for said section, are hinged, respectively, by their bottom parts to the opposite ends of the bottom of the main case section, so that the article holders can freely be swung or tilted inwardly and outwardly of the main case section, the arrangement being such that when the article holders are swung or tilted inwardly, their open top ends will be closed by the top of the main case section and that when, on the other hand, the article holders are swung or tilted out-

wardly, their open top ends will be exposed exteriorly of the ends of the main case section whereby the contents of the article holders are made accessible.

It is a further general object of my present improvements to provide a case or container especially adapted as a holder for cigarettes which may be easily operated by the use of one hand to render its contents accessible, and may be manufactured and sold at relatively small cost.

With the above and other objects in view, the invention consists in the improved container and in the form, construction, and combination or combinations of parts as will be hereinafter more fully described, illustrated in the accompanying drawing, and subsequently incorporated in the subjoined claims.

In the drawing, wherein by way of example I have illustrated a preferred embodiment of the invention, and in which similar reference characters designate corresponding parts throughout the several views,

Fig. 1 represents a perspective view of a complete container made in accordance with the present invention, this view showing the container as it appears when looking toward the bottom part thereof, with the article holders in closed position;

Fig. 2 represents a perspective view of the container in more or less upright position with the article holders swung into open position; and

Fig. 3 represents a vertical sectional view through the container with the article holders in open position.

Referring in detail to the figures of the accompanying drawing, wherein I have illustrated one preferred embodiment of my invention, the form of construction comprises a main case section designated generally by the numeral 10 and represented as consisting of a box-formed body having opposing side walls 11-11 connected at the top by a wall 12 and at the bottom by a wall 13, considerably shorter than the top wall 12, said opposing sides 11-11 gradually decreasing in length from the top wall 12 to the bottom wall 13 so as to provide downwardly converging edges 14-14. Thus constructed, the main case

section has opposite obliquely inclined open ends.

The device for carrying two allotments of cigarettes or other commodities comprises two separate actuatable box-body holders 15 15, made to have sliding fit between the side walls 11 11 of the case section and to swing or tilt between the top and bottom walls 12 and 13 thereof, upon suitable hinge means 16 16 arranged at the open ends of the bottom wall 13 of the main case section and connecting thereto the bottoms 17 17 of the article holders, it being best noted from an inspection of Fig. 3 that the bottoms 17 17 are thus hingedly connected intermediate their length to the bottom wall 13. In this arrangement the article holders are swingable or tiltable in the open ends of the case section; and when said article holders have been swung into closed position with their bottom wall portions 18 18 overlying the inside surface of the bottom wall 13, they constitute complementary end closures for the case section and their top ends, which are open, are covered by the top wall 12 of the case section.

Upon the outer faces of the corresponding side walls 19 19 of each article holder side parts 20 20 are suitably secured having obliquely inclined edges 21 21 adapted to abut against the inclined edges 14 14 of the side walls of the case section and thereby limit the inward movement of the article holder to closed position. Owing to the provision of the side parts 20 20, the exposed outside faces of the article holders will be entirely flush with the outside faces of the case section when the article holders are in closed position. By this construction, when the article holders are closed as represented in Fig. 1, no projections of any kind appear on the outside surface of the container structure.

For the purpose of determining the limit of the opening movement of the article holders, I prefer to provide a common flexible member 22 fixed at its central portion at 23 to the top wall 12 of the case section and having its opposite ends attached as at 24 24 to the inner end walls 25 25 of the two article holders. In addition to this, I may also provide for each article holder a suitable flexible member 26 having a portion 27 secured flatwise upon the inner surface of the bottom wall 13 of the case section and a portion 28 secured flatwise upon the outer face of the exposed portion of the bottom wall 17.

When the container is produced from cardboard or similar material, the flexible members 26 may be used to reinforce the hinge connection between the bottom walls 17 of the article holders and the bottom wall 13 of the case section; or it may even be made, for the sake of simplicity and cheapness, so that it will itself constitute the hinge connection on which the article holder turns. The bottom wall 13 of the case section, midway

the length thereof and between the regions where the flexible member portions 27 27 are attached thereto, is provided with a finger receiving opening 29 therein through which the finger may be projected upwardly to exert pressure upon the bottom walls of the two article holders for the purpose of tilting them either one at a time or both at a time into open position.

The corresponding side walls 19 19 of each of the article holders are by preference deeply and intermediately cut away to provide openings 30 30 in communication with the open top ends, so that the cigarettes or other commodities can be readily grasped by the fingers when the article holders are in open position. For securing the article holders, when they are in closed position, to the top wall 12 of the case section, suitable means may be provided in the form of catch pieces 31 31 applied to said top wall 12, and cooperating detent pieces 32 32 applied to the upper ends of the exposed walls 33 33 of the article holders. From an inspection of the drawing, it will be seen that the article holders, irrespective of whether they are in open position or in closed position, always extend partway into the case section; and further that when the article holders are closed the meeting edges 21 and 14 constitute diagonal lines of separation which extend from the hinge connection 16 to points at the opposite ends of the top wall 12 of the case section.

From the foregoing description considered in connection with the accompanying drawing, the construction and various advantages of my invention will be clearly understood. It will be apparent that such a case or container may be inexpensively produced from cardboard or similar material as an original container for cigarettes or other commodities, or it may be manufactured in more expensive form from wood, silver or gold or other material. When closed, the container presents a very neat and attractive appearance, and also effectively preserves its contents against breakage or deterioration. The container can also be easily and quickly manipulated and access to the contents thereof readily obtained.

While I have herein disclosed the preferred embodiment of my invention, it is to be understood that the construction of the parts as exemplified in the accompanying drawing may be altered or modified in many particulars, and I accordingly reserve the privilege of resorting to all such alterations and modifications as may be fairly incorporated within the spirit and scope of the invention as claimed.

I claim:

1. A container of the character described comprising a box-formed case section having side walls receding from the top wall to the bottom wall and having open ends between

the top and bottom walls, article holders arranged at said open ends and extending part way into the case section, said article holders having bottom walls and open tops, hinge means connecting the bottom walls of the article holders at intermediate points with the ends of the bottom wall of the case section, to provide for tilting the article holders to and from a position in which their open tops will be exposed adjacent said open ends, 10 there being an opening in the bottom wall of the case section through which to enter a finger and exert pressure upon the bottom walls of the article holders whereby to tilt the article holders into position for exposing 15 their open tops.

2. A container for cigarettes and the like comprising a frusto-shaped case section having side walls receding from the top wall to the bottom wall, and have open ends between the top and bottom walls, complementary article holders arranged at said open ends, having bottom walls and open tops, and forming with the case section a square-shaped configuration, hinge means at the end of the bottom wall of the case section connecting the bottom walls of the article holders at intermediate points with the ends of the bottom of the case section for tilting the complementary article holders in and out of the casing so that the open tops and part of the side walls of said holders are incased by the top and side walls of the case section and moved away from said walls, respectively, said article holders forming with the frusto-shaped case section when they are tilted therein a square-shaped container.

In testimony that I claim the foregoing as my invention, I have signed my name hereto.

CHARLES L'ENFANT.
